MACHINE FOR ROLLING RODS OR WIRE.

No. 599,338.

Patented Feb. 22, 1898.

UNITED STATES PATENT OFFICE.

ABEL KENWORTHY, OF WATERBURY, CONNECTICUT, ASSIGNOR TO THE BENEDICT & BURNHAM MANUFACTURING COMPANY, OF SAME PLACE.

MACHINE FOR ROLLING RODS OR WIRE.

SPECIFICATION forming part of Letters Patent No. 599,338, dated February 22, 1898.

Application filed February 3, 1897. Serial No. 621,760. (No model.)

To all whom it may concern:

Be it known that I, ABEL KENWORTHY, a citizen of the United States, residing at Waterbury, in the county of New Haven and State 5 of Connecticut, have invented certain new and useful Improvements in Machines for Rolling Rods or Wire, (Case C;) and I do hereby declare the following to be a full, clear, and exact description of the invention, such as will enable others skilled in the art to which it applies to make and use the same.

This invention relates to machines for making wire from rods or reducing the diameter and increasing the length of rods or wire, and 15 has particular reference to that type of machines which operate upon the metal by rolling as distinguished from drawing.

Among other objections to the method of drawing are the slowness, as compared with 20 rolling, and the fact that the rods or wire must be pickled and washed between successive operations after annealing, for the reason that the black coating on the wire as it comes from the annealing-furnace interferes 25 with the action of the die and with the production of perfect wire.

In another concurrently-filed application, Serial No. 621,758, I have shown a machine which gives a double reducing operation during a single pass of the wire, both sets of reducing-rolls being positively driven, but at different speeds, and in another concurrently-filed application, Serial No. 621,759, I have shown a machine which also gives a double 35 reducing operation during a single pass of the wire, the first reducing-rolls being idle-rolls—*i. e.*, not driven—while the second reducing-rolls are positively driven and serve to feed the wire through both sets; but in the 40 use of this last-mentioned machine it is necessary that the end of the wire or rod shall be first primarily reduced or “pointed” for a short distance in order that the said end may be readily pushed between the non-driven rolls by the attendant until the end is 45 grasped by the driven reducing-rolls, so that the wire may then be automatically passed through the machine and given two reductions at a single pass.

In the present invention I have embodied 50 somewhat of the principles of both of the other machines referred to in that while the first set of rolls is positively driven for a short time to pass the end of the wire to the second set and give the primary reduction, yet after 55 the second set begins to act and give the second reduction the rolls of the first set cease to be driven and become “idler” reducing-rolls. In this machine, therefore, I dispense with the necessity of first pointing 60 the wire and also avoid the difficulties sometimes experienced in securing the nicety of adjustment of speed between the two sets of rolls positively driven. The present machine, moreover, is not only adapted to give 65 two reductions during each pass of brass wire, but is also adapted to give four reductions during a single pass of copper wire. To explain the desirability of this feature, I will state here that in order to produce the best 70 results in brass wire it should be annealed after it has been given two reductions, while copper wire does not require this treatment. In this machine I have also provided an improved coiling-drum especially adapted for 75 this type of machine and certain other improvements, all of which I will proceed to describe, and then specify more particularly in the claims.

In the accompanying drawings, Figure 1 80 represents a plan view of the complete machine. Fig. 2 represents a side elevation of the same. Fig. 3 represents a detail elevation of the first pair of reducing-rolls and the means whereby they are adapted to be 85 driven or to become idlers. Fig. 4 represents a section on line X X of Fig. 3. Fig. 5 represents a detail elevation of the coiling-drum, portions thereof being broken away to show the interior, part of the outer end of 90 the drum being in section on the line Y Y of Fig. 6. Fig. 6 represents an end view from the right of Fig. 5. Fig. 7 represents a detail of the mechanism for automatically starting the drum. The relative positions of the 95 parts shown in this figure can readily be seen by comparing it with Fig. 1 after placing one of the sheets with the signatures uppermost.

Fig. 8 represents a detail, partly in section, from a point below Fig. 7. Fig. 9 represents a detail view from the position shown by the arrow, Fig. 8, said Fig. 9 being an enlargement of some of the parts shown in Fig. 6.

Similar reference characters indicate similar parts in all the views.

The bed of the machine is indicated in Figs. 1 and 2 at A, suitable standards or legs therefor being indicated at a. Near each end of the bed is a rolling mechanism, the one at the left being indicated in its entirety by B and the one at the right being indicated in its entirety by B'. These two mechanisms are substantially identical with each other, except that the second one (at the right) is provided in practice with rolls adapted to give greater reduction to the wire. Since the rolls of the said second mechanism when used must have greater surface speed than the first, I have indicated one way of accomplishing this by providing larger reducing-rolls and by having its main driving-pulley b' smaller than the main driving-pulley b of the first mechanism, these pulleys being driven by one belt, as at C. The said belt also passes over an intermediate pulley d.

The two reducing-machines B and B' being substantially alike, reference to the mechanism of one will suffice for both, similar parts in the second machine having a prime-mark after the reference-numerals.

The first reducing-rolls 1 are mounted in boxes adjustably supported in a frame or casting 2, the gearing for adjusting the boxes being indicated at 3. The two rolls 1 are geared together, as at 4, and the lower end of one of the shafts is made angular. (See Figs. 3 and 4.)

On this angular portion is fitted a sleeve 5, having a ratchet-toothed face, said sleeve being adapted to slide on the shaft, but not to rotate thereon. A shaft 6 abuts against the end of the sleeve-carrying shaft and is provided with a ratchet-toothed disk 7 to engage the teeth of sleeve 5 and rotate it and the rolls. The shaft 6 is driven continuously by means of the shaft 8 under the bed through the medium of bevel-gears 9 on the shafts 6 and 8, the direction of rotation being to feed the wire through the rolls and reduce it.

The second reducing-rolls 10 are mounted in boxes adjustably supported in a frame or casting 11, the gearing for adjusting the boxes being indicated at 12. The two rolls are geared to rotate together, the shaft of one of them being indicated at 13, and driven by the pulley b or b'. The speed of rotation of the second reducing-rolls is sufficiently greater than the initial driven speed of the first reducing-rolls to insure that after the wire has been taken by the second rolls it will be caused to travel between the first rolls at a speed faster than that imparted by the shaft 6, the ratchet connection at 5 and 7 permitting this, owing to the sleeve 5 being free to rise and move faster than the disk 7. Therefore while the rolls of

the first set are positively driven at first to carry the end of the wire through to the second set and give the first reduction after the wire is taken by the second set and further reduced and moved faster the first set become idle-rolls, but still reducing-rolls. After the wire leaves the second reducing-rolls it passes to the coiler, if the latter is to be used, as for brass wire. This coiler consists of a shield 14, secured to a standard 15, adapted to slide in ways transverse to the bed A, said shield being cut, as at 16, the portion at the left of which is bent outward. Back of the outwardly-bent portion are two rolls 17, between which the wire is passed, said wire being then deflected and given a downward curve by means of a roll 18, the wire then coiling up and around a stud 19, projecting from the outer face of the outwardly-bent portion of the shield. This coiling device is capable of taking as much brass wire as is commonly handled in single coils which must be placed in the annealing-furnace; but when copper wire is to be reduced it is passed through the rolling-machine B' as well and is therefore given four reductions. At this time the shield 14 is detached from the standard 15, and the latter is moved out of the way by means of the sliding support. (See dotted lines in Fig. 1.) The treatment of wire in the second reducing-machine B' is the same as in the first machine B, the shaft 6' being driven from the shaft 8, and the latter being driven from a shaft 20, having the pulley d, the reducing-rolls 10' of this mechanism being driven by pulley b'.

As shown in Fig. 2, the gearing at the right of shaft 8 is such as to drive the vertical shaft 6' considerably faster than the shaft 6.

It will now be understood that as a whole this machine comprises four sets of reducing-rolls, the second and fourth of which are always driven, while the first and third are idler reducing-rolls during all but the initial operation of passing the end of the wire to the driven rolls, and all four sets operate to successively reduce the wire four times during a single pass. This insures much greater production in a given time than has been accomplished by any machine or set of machines that I am aware of.

Since copper wire is treated in much greater quantities as to the length and weight of single pieces, I have devised a coiling-drum which is adapted to receive and retain a much greater weight and length than the coiling device above described for brass wire.

To one end of the bed A are secured two brackets 21 21, one of which has a standard 22. A shaft 23 is mounted in the brackets 21 and projects at one end to support the drum, presently described. On the shaft is mounted a pulley 24, driven by a belt. (Not shown.) This pulley is adapted to be connected at times to the shaft to drive it by means of a suitable clutch, one member of which is indicated at 25. Since there is nothing novel

in the particular clutch used, I have not attempted to show it in detail, it being sufficient to state that the clutch is operated by means of a lever 26, pivoted at 27 and connected to the clutch member by collar 28, a spring 29 being connected to the lever to cause the latter when released by a catch, presently described, to operate the clutch so as to connect the pulley with the shaft.

10 On the outer end of the shaft is secured the drum 30, having a flange 31 and a slot 32 from the flange to the outer edge. This drum is supported on the shaft by the arms 33 at the outer end in order that the inner end of the drum may receive and rotate around the latch and bending-stud, presently described, and which project from the standard 22 within the flanged end of the drum.

15 The latch 34 (see Figs. 7, 8, and 9) is pivoted at 35 to the standard 22 and has its hooked end adapted to engage the outer side of the upper end of lever 26 to hold it in the position shown in Fig. 5 when the drum is to be stationary. The other end of the 20 latch is flattened to form a plate 36, which lies in the path of movement of the end of the wire, which is directed by the last set of reducing-rolls through an opening 37 in the drum at the inner end of and communicating 25 with the slot 32. When the end of the wire abuts against plate 36, it actuates the latch to release the lever 26, and then the spring 29 causes the lever to operate the clutch to start the drum.

30 The bending-stud 38 is mounted to rotate freely in a bearing in the standard 22 and projects inside the drum between plate 36 and the hole 37. (See Fig. 9.) This stud is provided with a hole 39, one end of each side 35 wall of the hole 39 being rounded, as at 40. The wire entering hole 37 passes into and through the hole 39 until it abuts against the plate 36. The drum instantly begins to rotate in the direction of the arrow, Fig. 9, and the lower side of the slot 32 in the drum carries the wire upward, and the stud 38 rotates half-way, thus causing the end of the wire to be bent so as to hook the end of the wire over the lower edge of the slot of the drum, the 40 rounded edge 40 of the slot 39 preventing too sharp a bend being given. To retain the stud in its half-rotated position, so as to be ready to receive the end of another piece of wire, I provide a detent-spring 41, (see Figs. 6 and 9,) 45 secured to the standard and having a rounded end adapted to engage a recess 42 in one or the other side of the stud.

50 To retain the drum in the proper position, to which it may be turned by the attendant, to insure the entrance of the wire through the hole 37, I provide a bolt 43, mounted in the standard 22 and having a beveled end adapted to enter a recess 44, properly located in the flange of the drum. The rear end of this bolt 55 is formed as a sleeve 45, which receives the pin 46, said sleeve being slotted, as at 47, to

receive a pin 48 in the standard. A pin-and-slot connection at 49 permits the sleeve and pin to have a limited relative movement, and a spring 50 is confined between the end of sleeve 45 and the head of pin 46. The outer surface of the head of pin 46 is acted upon by the upper end of lever 26 to hold it in the position shown in Figs. 5, 7, and 8 when the drum is not being rotated; but should the 70 drum stop with its recess 44 not opposite the bolt 43 it is to be rotated by the attendant until the spring 50 forces the bolt into the recess. As soon as the lever 26 is released the bolt is free, and the inclined side of the recess 80 44 moves the bolt outward as the drum begins to rotate.

The outer end of the drum is provided with movable stops adapted to be projected outward when the drum begins to rotate, so as to retain the coil thereon. Secured to the shaft inside the drum is a hub 51, having levers 52 pivoted to it, the outer ends of the levers being connected, by a yoke-and-pin connection, with rods 53, mounted to slide in ways of the arms 33, and the outer ends of said rods being adapted to project outward from the periphery. A sleeve 54 is mounted to slide on the shaft and is connected with the levers 52 by links 55. This sleeve 54 is connected, 95 by means of a pin 56 passing through a slot 57 in the shaft, with a rod 58, which is movable longitudinally within the shaft, said rod being indicated by dotted lines in Fig. 5. The other or inner end of the rod 58 is connected, 100 by means of a pin 59 passing through a slot 60 in the shaft, with the clutch member 25. The construction is such that as soon as the lever 26 is operated to start the drum the rod 58 causes the sleeve 54 to move toward the 105 left, as shown in Fig. 5, and the toggle-links 55 cause the levers 52 to eject the sliding rods 53, so as to prevent the coil from passing off the drum. The drum is slightly tapered, and after the coiling begins and the hook has been 110 formed in the end of the wire, as above described, the said hook begins to travel along the edge of the slot in the drum, said hook being first drawn freely out of the hole 39 in the bending-stud 38. When the piece being 115 operated upon is finished, the attendant operates the lever 26 by any suitable means, so as to unclutch the drum-shaft from the driving-pulley, and at the same time the rod 58 is moved so as to retract the rods 53 within 120 the drum, leaving the heavy coil free to be removed.

It is to be understood that the rolls of the four pairs or sets 1, 10, 1', and 10' are so grooved and mounted relatively to each other 125 that as the wire is passed from rolls 1 to 10' it is given four successive reductions to four successively smaller sizes.

When the two reducing mechanisms, which I have indicated in their entirety by B and 130 B', are employed, it is desirable that there shall be provision for operating the mechan-

ism B' at a speed always sufficient to prevent either a pushing or a dragging action on the wire between the two mechanisms. To accomplish this, I connect the pulley b' with the shaft 5 13' by an ordinary form of friction-clutch, which is automatic in its action, according to the resistance to the power afforded by the belt-pulley. This clutch I have indicated at 70 in Fig. 1, partly by full lines and partly 10 by dotted lines, and have not deemed it necessary to illustrate or describe it in detail, since any of the well-known automatic clutches may be employed.

Having thus described my invention, I 15 claim—

1. A wire-rolling machine comprising in its construction two sets of positively-driven reducing-rolls, an intermediate coiling device for use in connection with the first set of rolls, 20 and a coiling device beyond the second set for use in connection with both sets of rolls.

2. A wire-rolling machine comprising in its construction two sets of positively-driven reducing-rolls, an intermediate coiling device, 25 a second coiling device beyond the second set of said rolls, and idler reducing-rolls in front of each set of positively-driven rolls.

3. A wire-rolling machine comprising in its construction two sets of positively-driven 30 rolls, an intermediate coiling device, means for displacing the said coiling device from the path of movement of the wire between the rolls, and a coiling device beyond the second set of rolls.

35 4. A wire-rolling machine comprising in its construction two sets of continuously-driven reducing-rolls, an intermediate coiling device for use in connection with the first set of rolls, a pair of reducing-rolls in advance 40 of and having means for driving them at a slower speed than the continuously-driven set, means for disconnecting the power from the slow-speed rolls when the wire is taken by the rolls having the higher speed, and a 45 coiling device beyond the second set for use in connection with both sets of rolls.

5. A wire-rolling machine comprising in its construction two pairs of continuously-driven reducing-rolls, a pair of intermittently-driven 50 reducing-rolls adapted to be disconnected from the driving power when the wire is taken by the first-mentioned rolls, an intermediate coiling device for use in connection with the first set of rolls, and a coiling device 55 beyond the second set for use in connection with both sets of rolls.

6. A wire-rolling machine comprising in its construction two sets of continuously-driven reducing-rolls, an intermediate coiling device 60 for use in connection with the first set of rolls, a pair of reducing-rolls arranged in advance of each set of positively-driven rolls and mounted to turn freely under the influence of a rod or wire passed through them by the first-mentioned rolls, means for positively driving 65 the freely-mounted rolls at the beginning of

the operation, and a coiling device beyond the second set for use in connection with both sets of rolls.

7. A wire-rolling machine comprising in its 70 construction two pairs of continuously-driven reducing-rolls 10 and 10', two pairs of rolls 1 and 1' in advance of the continuously-driven rolls each of said pairs of rolls 1 and 1' being geared together, the shafts of one of the rolls 75 1 or 1' being angular and having a sliding sleeve 5 provided with ratchet-teeth and the shank 6 having the ratchet-toothed disk 7, an intermediate coiling device, and a coiling device beyond the second set of rolls for use in 80 connection with both sets.

8. The combination with a wire-rolling machine, of a coiling-drum, mechanism adapted to rotate the drum and including a clutch member, and controlling means located within the drum and in the path of movement of the end of the wire to actuate the clutch to 85 rotate the drum.

9. The combination with a wire-rolling machine, of a coiling-drum, a detent for holding 90 it stationary, mechanism including a clutch member for rotating the drum, and means located within the drum and in the path of movement of the end of the wire for releasing the detent and actuating the clutch to 95 rotate the drum.

10. The combination with a wire-rolling machine, of a coiling-drum, means for automatically bending the end of the wire to cause 100 it to engage the drum, mechanism adapted to rotate the drum and including a clutch member, and controlling means located within the drum and in the path of movement of the end of the wire to actuate the clutch to rotate the drum. 105

11. The combination with a wire-rolling machine, of the drum 30 having slot 32 and hole 37, the standard having the rotary stud 38 provided with hole 39, and means for rotating the drum. 110

12. The combination with the shaft 23 and means, including a clutch member, for rotating it, of the lever 26 for actuating the clutch member, the drum 30 having a wire-receiving slot or opening, the latch 34 pivoted to a part 115 of the frame and adapted to hold the lever 26 and having a plate or extension 36 in the path of movement of the end of the wire entering the drum, and a detent for temporarily holding the drum in position on its axis. 120

13. The combination with the shaft 23 and drum 30, of the radially-movable rods 53, the hub 51 fixed on the shaft, the levers 52 pivoted to the hub and connected with said rods, the sliding sleeve 54 on the shaft, the links 55 125 connecting the sleeve with the levers, and means for moving said sleeve along the shaft.

14. The combination with the shaft 23 and drum 30, of the radially-movable rods 53, the hub 51 fixed on the shaft, the levers 52 pivoted to the hub and connected with said rods, the sliding sleeve 54 on the shaft, the links 55 130

connecting the sleeve with the levers, the rod 58 longitudinally movable in the shaft and connected with the sleeve 54, means, including a clutch member, for connecting the shaft 5 with driving power, and connections whereby movement of the clutch member is imparted to said rod 58.

In testimony whereof I affix my signature in presence of two witnesses.

ABEL KENWORTHY.
